UNITED STATES PATENT OFFICE.

HENRI GALLET, OF MONTREAL, QUEBEC, CANADA, ASSIGNOR TO INDUSTRIAL CORPORATION LIMITED, OF MONTREAL, QUEBEC, CANADA.

MACHINE FOR MAKING FASTENERS.

Application filed June 4, 1923, Serial No. 643,268. Renewed February 18, 1928.

This invention relates to means for making and fastening clasps on a fabric strip, and the objects of the invention are to provide an improved means whereby clasps are punched and individually delivered to a fabric strip and placed and fastened thereon in a continuous operation, and the fabric is thereafter wound on a spool ready for any use to which it may be applied, such as on 10 garments, bags, and other articles too numerous to be specifically mentioned herein.

Further objects are to simplify the construction of the mechanism and properly time the several parts so that they will synchronize and automatically cooperate, in this way increasing the efficiency and well 15 working of the machine.

Further objects still are to render the machine compact in construction, economical, 20 and to so arrange the several parts that they are accessible for inspection and repair, and generally to adapt the several parts to better perform the functions required of them.

With the above and other objects in view 25 which will be made clear as the specification proceeds, my invention consists in the improved means for making and fastening clasps on a fabric strip, such as is described in detail in the following specification, illus- 30 trated in the drawings and more particularly pointed out in the appended claims.

For a better understanding of my invention reference is now made to the drawings in which:—

35 Figure 1 is a general plan view of the entire machine.

Fig. 2 is a side elevation of the same.

Fig. 3 is a vertical section taken on the line 3—3 of Fig. 1.

40 Figure 4 is an enlarged fragmentary view of the carrier and feeding mechanism.

Figure 5 is an enlarged fragmentary sectional view taken on the line 5—5 of Figure 1.

45 Figure 6 is a fragmentary sectional view taken on the line 6—6 of Figure 5.

Figure 7 is a diagrammatic view showing the various steps of the clasps setting and fastening means in operation.

Like characters of reference refer to like 50 parts in the drawings.

Referring to the drawings, I have illustrated conventionally a power press 8 embodying well known mechanical parts which it is not deemed necessary to illustrate or 55 describe, the press 8 being provided with a

pulley 9 which may be driven from any suitable source of power.

In front of the press 8 I have arranged a pair of feed rollers 11 which are properly timed and actuated by the press so that 60 they synchronize with the movement thereof, and the band of metal 10 is fed to the feed rollers 11 step by step so that clasps are punched from the band during the progressive feeding thereof. 65

The metal band 10 is fed to the punching and forming dies 12 and each clasp as it is punched is automatically picked up and delivered to a conveyor by the rocking arm 51 which is mounted beneath the said dies. 70

This rocker arm is provided with an arm 52 which is connected to one end of a spiral spring 52^a, the other end of which is secured to a convenient part of the power press, and the rocker arm is also formed with a projection 50 which coacts with a stop 53. 75

This rocker arm is actuated by an adjustable member 49 operatively attached to a reciprocating part 48 of the power press 8, and this member engages the projection 50 and 80 rocks the arm in one direction against the action of the spring 52^a, and the movement of the arm in the opposite direction is limited by the stop 53.

The rocker arm 51 when actuated by the 85 member 49 engages the punched clasp and delivers it to the conveyor and to this end the rocker arm extends into a slot in the end of the carrier portion 14 of the conveyor adjacent to the power press. 90

The conveyor consists of a carrier 14 formed of an elongated strip of metal having its lateral edges bent to overhang the body of the strip, the said edges being spaced to form a central passageway or guide 2 for an object 95 to be made clear hereafter.

Cooperating with the carrier 14 is a feeder 13 provided on one longitudinal edge with serrations from which fingers 22 depend into the passageway or guide 2, to engage the 100 clasps in the carrier 14, and this feeder is formed on the opposite longitudinal edge with projections or lugs 3 which carry a rod 4 slid- 105 ingly mounted in brackets 5 secured to the base 45 of the machine.

This feeder is designed to be reciprocated and is provided with a collar 20 adjustably mounted on the rod 4, the collar being connected to one end of a spiral spring 21 the other end of which is attached to a bracket 5. 110

The collar has a depending arm 7 which carries a roller 19 designed to coact with a cam 18 mounted on the transversely extending shaft 16 which is journalled in bearings 8¹ and driven by a chain drive 17 from the power press 8.

The feeder is thus positively fed forwardly by the cam 18, and the retrograde movement is brought about by the spring 21.

As the feeding of the clasps is in a step by step movement, the feeding steps are made during the forward movement of the feeder, and the feeder is tilted about the axis of the rod 4 during the retrograde movement of the feeder thereby disengaging the fingers 22 from the clasps, and the fingers engage other clasps at the beginning of the next forward stroke, so that in this way a positive progressive feeding of the clasps along the carrier 14 takes place.

By forming the carrier 14 with overhanging side walls the path of travel of the clasps is well defined and lateral displacement of the clasps is impossible.

The tilting of the feeder 13 is accomplished by a projecting pin 23 depending from the feeder, which pin coacts with the pivotally mounted plate 24 which is spring pressed into the path of the pin during the retrograde movement of the feeder.

This plate is formed with an inclined plane 26, which when the pin 23 is riding thereover causes the feeder to be tipped laterally to disengage the fingers 22 from the clasps, and after the pin 23 has become disengaged from the inclined plane the fingers 22 engage the adjacent clasps to carry on the feeding operation.

The plate 24 is displaced laterally during the forward stroke of the feeder by the pin 23 engaging the back of the plate, and as soon as the pin passes the plate, the said plate is spring pressed back into normal position so that the inclined plane 26 is in the path of the pin 23 on the retrograde movement of the feeder.

As the clasps reach the end of the carrier 14 they are positioned on a fabric strip 34 which is fed across the path of the clasps through a slot in the end of the carrier.

This fabric strip is unwound from a bobbin 47 supported from the lower side of the base 45, and the fabric strip passes around a spring controlled tension pulley 46, after which it passes between the charging wheel 43 and the coactting roller 44, the fabric strip being then wound on the bobbin 42.

The movement of the fabric strip synchronizes with the movement of the conveyor which delivers the clasps to the said strip.

To bring about this movement of the fabric strip I mount cams 27 on the shaft 16 and these cams coact with the rollers 28 mounted on the ends of the longitudinal arms 29 and 30, the opposite ends of the arms being en-

gaged by springs 36 which tend to press the rollers 28 against the face of the cams 27.

The arm 30 is provided intermediate of its length with a cam 37 which engages a roller 38 carried by a slide 39, one end of which is fixed to an upright arm 40 carrying at its upper end a ratchet means 41 actuating the charging wheel 43 whereby the fabric strip is fed from one bobbin to the other across the path of movement of the 75 clasps on the carrier 14.

The slide 39 is spring controlled in one direction so that the rollers 38 will properly engage the cam 37.

The arms 29 and 30 are each provided with 80 cams 31 which engage with the spring controlled roller 32 carried by the setting members 33 which are arranged in pairs working in unison to position and fasten the clasps on the fabric strip 34.

The slot formed in the carrier 14 has, all along where the fabric strip passes through at 35, slightly overhanging edges to prevent the clasps from jumping out and becoming displaced, the facing ends of the setting members 33 being also made with slightly overhanging edges so as to securely hold the clasp while it is being fixed to the fabric strip 34.

The cams 31 have a dual action upon the 95 member 33 which are normally held apart to clear the moving fabric strip 34, the first step of the action being to localize and hold the clasp to be set in position, and the second step to properly set and fasten the clasp to 100 the fabric strip 34.

The operation of the machine is as follows:

The band of metal 10 is fed to the rollers 11 and thence passes to the forming and punching dies 12.

The punching die 12 pushes each clasp downwardly on the end of the carrier 14 whereupon the rocker arm 51 being actuated enters the longitudinal slot in the end of the carrier 14 and individually feeds each clasp 110 to the carrier.

When a clasp has thus been placed on the carrier 14 it is engaged by the fingers 22 of the reciprocating feeder 13 and positively fed in a step by step movement along the carrier. 115

When a clasp reaches the end of the carrier it is straddled on the fabric strip 34 and fastened thereon by the setting members, and the fabric with the clasps is fed to the bobbin 42 and wound thereon ready for use.

From the above description it will be seen that I have invented a simplified means for making and fastening clasps on a fabric strip the means being such that it is simple in construction, readily accessible, practically fool-proof, and not liable to go out of repair.

What I claim as my invention is:

1. A device of the class described, means for stamping clasps from a progressively fed strip of metal, a rocker arm for individually 130

delivering the clasps to a carrier, means for actuating the rocker arm, a feeder for moving the clasps progressively along the carrier, means for feeding a strip of fabric across the carrier at the end thereof, and means for placing the clasps on the fabric and fastening them thereon.

2. In a device of the class described, means for stamping clasps from a progressively fed strip of metal, means for individually feeding the clasps to a carrier, a reciprocatory feeder, means for tilting the feeder about a longitudinal axis during the retrograde movement of the feeder, means for feeding a strip of fabric across the carrier at the end thereof, and means for placing the clasps on the fabric and fastening them thereon.

3. In a device of the class described, means for stamping clasps from a progressively fed strip of metal, means for individually feeding the clasps to a carrier, a feeder for mov-

ing the clasps progressively along the carrier, cam controlled means for moving the feeder in one direction, resilient means for moving the feeder in the opposite direction, means for feeding a strip of fabric across the carrier at the end thereof, and means for placing the clasps on the fabric and fastening them thereon.

4. In a device of the class described, means for stamping clasps from a progressively fed strip of metal, means for individually delivering the clasps to a carrier, a feeder for moving the clasps progressively along the carrier, means for feeding a strip of fabric across the carrier at the end thereof, and cam-actuated means for first placing the clasps on the fabric and subsequently fastening the clasps on the fabric.

Signed at Montreal, Quebec, Canada, this 7th day of May, 1923.

HENRI GALLET.
